UNITED STATES PATENT OFFICE.

ORRELL ASHTON, DECEASED, LATE OF SWAMPSCOTT, MASSACHUSETTS, BY HANNAH ASHTON, EXECUTRIX, OF WOLLASTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PULLING-OVER MACHINE.

1,319,261.

Specification of Letters Patent. Patented Oct. 21, 1919.

Application filed November 2, 1916. Serial No. 129,215.

To all whom it may concern:

Be it known that ORRELL ASHTON, late of Swampscott, in the county of Essex and State of Massachusetts, deceased, invented 5 certain Improvements in Pulling-Over Machines, of which the following description, in connection with the accompanying drawings, is a specification, like reference characters on the drawings indicating like parts 10 in the several figures.

This invention relates to machines for use in the manufacture of boots and shoes for pulling the upper materials over the last. The invention is herein disclosed, by way 15 of example, as applied to a machine of a well known type such as shown in United States Letters Patent No. 663,777, granted on Dec. 11, 1900 on the application of R. F. McFeely, and as embodied in mechanism for 20 effecting adjustment lengthwise of the last of the grippers which engage and pull the upper at the sides of the last. In the machine shown in said patent the side grippers are connected for movement simultaneously 25 in opposite directions lengthwise of the last for the purpose of adjusting the upper in such manner as to position the tip line in the proper transverse relation to the last, and similar movement also may be imparted 30 to one of the grippers, selected by the operator, independently of the other gripper, both for angularly adjusting the tip and for positioning the tip seam at the proper distance from the toe end of the shoe. An 35 important object of this invention is to provide an improved construction of gripper adjustment mechanism whereby adjustment may be more readily and accurately effected and the upper may be more effectually retained in the required position than in prior 40 constructions.

To the above and other ends, an important feature of the invention consists in the combination with a gripper adjustable lengthwise of the bottom edge of a last, of novel means for retaining the gripper in any position of adjustment against the tendency to displace the gripper from such position in the subsequent operation of the machine

upon the shoe. The construction shown 50 comprises friction means normally effective to insure against accidental displacement of the gripper while permitting manual adjustment of the gripper in either direction. The invention also provides novel means for releasing the gripper to permit its return movement lengthwise of the edge of the last to a normal position of rest, and such means constitutes another important feature. In 55 the construction shown the invention is illustrated in its application to side grippers which are adjustable lengthwise of the last for tip straightening.

A further feature of the invention consists in a novel combination and arrangement 60 comprising opposite side grippers either or both of which may be adjusted lengthwise of the last, each independently of the other, whereby precise and accurate adjustment of the upper on the last is facilitated.

The construction herein shown includes means for moving the side grippers together toward the toe end of the last for the purpose of effecting in a well known manner a forward draft of the upper, and a further 65 feature of the invention resides in the combination of such means with means whereby the grippers may be adjusted lengthwise of the last independently of each other. It should be understood, however, that as to 70 other features hereinbefore enumerated the invention, in its broader aspects, is not necessarily limited to a construction including provision for a forward draft of the 75 upper.

The above and other features of the invention, including certain details of construction and combinations of parts, will now be described with reference to the accompanying drawings and pointed out in the 80 claims.

In the drawings:

Figure 1 is a view in side elevation of a portion of a pulling-over machine including mechanism in which the invention is embodied.

Fig. 2 is a perspective view of the side grippers and associated parts, with a por-

tion of the mechanism broken away for the sake of clearness in the illustration,

Fig. 3 is a view in front elevation of a portion of the mechanism seen in Fig. 2, 5 with parts broken away for the sake of clearness, and

Fig. 4 is a view in side elevation of a portion of the structure seen in Fig. 3.

The machine shown includes the usual toe 10 gripper 2 and side grippers indicated generally by the numeral 4, the side grippers being suspended from updraw levers 6 which are operatively moved in one direction to cause the side gripper jaws 8 to 15 hold the upper firmly and to stretch it over the last, and in the opposite direction to return the grippers to starting position. The connections between the side grippers and the levers 6, moreover, are such as to 20 permit lateral movement of the grippers in the usual manner to carry the margin of the upper over the bottom of the last and to cause the grippers to withdraw from the 25 paths of movement of the instrumentalities which operate subsequently to fasten the upper in position.

The position of each of the side grippers 4 lengthwise of the last is controlled by a pinion 10 in engagement with teeth on a 30 rack bar 12 to which the gripper is connected. The connection between the gripper and the rack bar is such as to permit the gripper to move upward and downward and also laterally with relation to the 35 bar, the connection comprising a pair of rods 14 and 16 pivoted together and normally positioned substantially at right angles to each other by engagement in slide-ways formed respectively on the rack bar 40 and on the gripper. Operative movements of the grippers accordingly may be effected without moving the rack bars and without interrupting their engagement with the teeth of the pinions 10.

45 Each pinion 10 is formed as a part of a sleeve 18 which encircles a shaft 20 and between which and the shaft there is provision for relative turning movement. A bracket 22 bolted to a portion 23 of the 50 machine frame in which the shaft 20 is journaled serves as a bearing in which the right hand sleeve 18 (Fig. 3) is rotatively mounted, and the other sleeve is similarly journaled in a bracket 24 on a frame member 25 in 55 which also the shaft 20 has a bearing. Clamped upon the outer end of each sleeve 18 is a disk 26 to which is connected a handle 28 whereby the sleeve may be turned on the shaft 20. The connection between the 60 handle 28 and the disk 26 comprises a ring 30 and spacing members 32 within which are bolts 34 which serve to clamp the ring to the disk. By means of washers 36 the bolts 34 serve also to retain the handle members 65 28 on the rings 30. It will now be apparent

that through its connection with the handle 28, comprising the disk 26 clamped on the sleeve 18, either of the grippers 4 may be adjusted lengthwise of the last independently of the other gripper.

70 In order that the grippers 4 may be retained effectually in adjusted position, there is associated with each of the sleeves 18 a friction clutch comprising a leather washer 38 serving as a friction member between the disk 26 hereinbefore described and a casting 40 which is secured on the end of the shaft 20. The members 26 and 40, which have plane faces for frictional engagement with the opposed plane faces of the 80 washers 38, are caused to press upon the washers 38 by the action of the wedge 42 positioned between an inclined bearing 43 on the stationary bracket 22 and a collar 44 which engages the right hand disk member 26 (Fig. 3). When the wedge 42 is moved into its operative position, as indicated in Fig. 3, it thus serves to slide the right hand disk 26 together with the corresponding sleeve 18 toward the right to 90 press the washer 38 between the disk and the casting 40, and after the movement of the right hand disk relatively to the casting 40 has been stopped by the washer 38, continued movement of the wedge serves to 95 move these parts and the shaft 20 together toward the right to cause the casting 40 at the opposite end of the shaft to press the adjacent washer 38 against the corresponding disk 26, endwise movement of this disk 100 and the sleeve 18 on which it is mounted being prevented by engagement of the end of the sleeve with the frame member 25. By means of the wedge 42 and the friction members 38 both sleeves 18 will thus be 105 clutched to the shaft 20, the pressure on the friction members being sufficient to prevent accidental displacement of either of the grippers 4 relatively to the other in directions lengthwise of the last while permitting either gripper to be adjusted relatively to the other by means of the respective hand lever 28.

110 The wedge 42 is normally positioned, by means to be hereinafter described, in such relation to the member 43 as to render the clutches effective to hold the sleeves 18 and the grippers in position. In order that either gripper may be readily and accurately adjusted as described, without affecting the 115 position of the other gripper, means is provided for overcoming the tendency of the shaft 20 to turn when either of the handles 28 is turned. In the construction herein shown this means comprises a portion of the mechanism provided for the purpose of moving both the side grippers 4 in a forward direction together to draw the upper forwardly on the last in a well known manner. This mechanism comprises a plate 48 hav- 120

ing a hub 50 loose on the left hand sleeve 18 and retained on the sleeve between the disk member 26 and a collar 52 secured to the sleeve, a spring controlled pin 54 carried by the adjacent casting 40 and arranged to enter some one of an arcuate series of holes in the plate 48 whereby the plate is locked to the shaft 20, and treadle means for turning the shaft through its connection with the plate. The treadle connection for operating the plate 48 comprises a rod 56, downward movement of which serves to turn the plate and connected parts in a direction to move the grippers forwardly, the reverse movement of the grippers being effected through the operation of the usual treadle spring 57. As the parts are positioned in Fig. 2, the forward draft, as well as the updraw, has been effected and the upper is under tension, the grippers being locked in their foremost position by means of a spring held pin 58 which is carried by the plate 48 and in this position of the parts engages under a catch 60 which may be conveniently carried by one of the usual side tacker arms. It will be understood that the forward draft on the upper is effected after the side gripper jaws have closed upon the upper at some time prior to the operation of the tacking instrumentalities, the tacker arms being positioned at this time at their outer limits of movement with the catch 60 in position to be engaged by the pin 58. When the side tacker arms move inward, after the upper has been stretched over the last, the catch 60 releases the pin 58, whereupon the side grippers are moved rearwardly through the action of the spring 57 as soon as they have released their hold upon the stock, the limit of rearward movement being determined by the engagement of a lug 62 on the plate 48 with a stationary pin 64. As the parts are then positioned, therefore, the shaft 20 is restrained from turning in one direction by the pin 64 in engagement with the lug 62 and in the other direction by the action of the comparatively strong treadle spring, and with the parts positioned as shown in Fig. 2, at the end of the forward draft of the grippers, the shaft 20 is restrained from movement in one direction by engagement of the pin 64 with a lug 66 on the plate 48 and in the other direction by engagement of the pin 58 with the catch 60. Movement of the grippers to adjust the position of the upper on the last is preferably effected while the upper is under tension at the end of the updraw movement and prior to the movement of the grippers for drawing the upper forwardly. In order to permit such adjusting movement of either gripper, the pressure upon the washers 38 is so proportioned to the strength of the treadle spring that either gripper may be adjusted in one direction by move-

ment of the corresponding handle 28 without causing the shaft to turn, movement of the shaft upon adjustment of either gripper in the opposite direction being prevented by the engagement of the pin 64 with the lug 62. Either gripper may thus be moved any desired distance lengthwise of the last independently of the other gripper, and after the relative adjustment of the grippers has been effected they are maintained in their relative positions by the clutch means which, without the necessity for any action on the part of the operator, is normally in condition to hold the grippers in their adjusted relation. The clutch means, moreover, provides a sufficiently positive connection with the shaft 20 to permit the forward draft of the upper to be effected by the operation of the treadle rod 56. The position of the wedge 42 is controlled through connection with a positively operated lever 68 (Fig. 1) which is a portion of well known means with which machines of the illustrative type are provided whereby, in the final stage of the cycle of operations, the lateral movements of the grippers and the tacker arms are controlled. With reference to Fig. 1, it will be understood that a movement of the lever 68 toward the left causes the grippers to move inward to carry the upper over the margin of the sole and also causes the tacker arms to move inward to tack inserting position, the grippers being tripped through the inward movement of the tacker arms to cause them to release their hold upon the upper before the tacks are driven, and that this movement of the lever 68 is followed by a reverse movement toward the right to relocate the grippers and the tacker arms in their starting positions. As the lever 68 moves toward the left the wedge 42 is forced out of its operative position by a connection between the lever and the wedge comprising a rod 70 and a stop 72 on the rod which engages a lug 74 on the wedge member. Pressure on the clutch members 38 is thus released, permitting springs 76 which are positioned in chambers in the castings 40 to act upon pins 78 which project from the disks 26 into the chambers between opposite ends of the respective springs, in such manner as to turn the sleeves 18 relatively to the shaft 20 and relocate the grippers in their normal relative positions as soon as they have released their hold upon the stock. It will be understood by reference to Figs. 3 and 4 that the opposite ends of each spring 76 normally engage a plate 80 on the casting 40, the plate being forked to receive the pin 78 between the ends of the spring. A normal angular position of each sleeve 18 on the shaft 20 is thus determined, and a turning movement of the sleeve relatively to the shaft causes the pin 78 to compress the

spring by pressure applied at one end or the other, the opposite end of the spring meanwhile engaging the plate 80 as an abutment. It will be understood that the 5 springs 76, while of sufficient strength to effect the relocation of the grippers, are not strong enough to overcome the friction on the members 38 when the wedge 42 is in operative position.

10 After the side grippers have been returned to their normal relative positions as above described, the movement of the lever 68 toward the right (Fig. 1) serves to set the clutches again by drawing the wedge 42 15 into operative position. Between the lug 74 through which the rod 70 is arranged to slide, and a nut 82 on the end of the rod is a spring 84 which is compressed during this movement of the lever 68 to hold the clutch 20 members engaged under yielding pressure.

In the operation of the machine, briefly summarized, the upper and the last are placed in a position in the usual manner and the edges of the upper are entered in the 25 grippers. At this time the side grippers 4 will occupy their rearmost positions, the lug 62 on the plate 48 engaging the limiting pin 64, and the wedge 42 will be positioned as shown for rendering the clutches at opposite ends of the shaft 20 effective to maintain the grippers in their normal relative locations. The machine will then be started and the updraw movement imparted to the 30 grippers, whereupon the machine will again come to rest with the upper under tension. By manipulation of the handles 28 the operator may then move one or both of the side grippers forwardly or backwardly as required for straightening the tin and positioning the tip seam in the correct angular relation to the last. If a forward draft of the upper is desired, the operator will then depress the treadle connected with the rod 56 until the pin 58 engages beneath the 35 catch 60, the pin 54 having been previously entered in the proper hole in the plate 48 to determine the desired limit of forward movement of the grippers. After these operations have been completed and the upper 40 has been clamped in the usual manner at the sides of the last, upon a further actuation of the starting mechanism movement of the lever 68 in one direction will be effected to cause the grippers to carry the margin of 45 the upper inward over the sole and the tacker arms to move toward driving position, the grippers finally releasing their hold upon the upper and the tacks being driven to hold the upper in place, and by continued 50 movement of the operating connections the movement of the lever 68 will be reversed and the parts will be returned to starting position. As the tacker arms move inward 55 the pin 58 is released and the treadle spring 60 rendered effective through the rod 56 and

the plate 48 to return the grippers to their rearmost position, the return of the grippers taking place upon their release from holding engagement with the stock. Through the first movement of the lever 68, moreover, 70 the pressure on the friction members 38 at the ends of the shaft 20 is released in the manner explained and the springs 76 are permitted to act upon the pins 78 to turn the sleeves 18 and cause the grippers to assume their normal relative locations as soon as they have been tripped. The movement of the lever 68 in the opposite direction will then cause the wedge 42 to render the clutches at opposite ends of the shaft 20 80 again effective to retain the grippers in their normal relative positions.

Having described the invention, what I claim as new and desire to secure by Letters Patent of the United States is:

85

1. In a machine of the class described, a side gripper for pulling an upper over a last, said gripper being adjustably movable different distances lengthwise of the last, means for retaining the gripper in adjusted 90 position, and positively operated means for operating said retaining means to release the gripper.

2. In a machine of the class described, a side gripper for pulling an upper over a last, said gripper being adjustable lengthwise of the last, a friction clutch comprising opposed members having substantially plane faces in frictional engagement for retaining the gripper in any position of said adjustment, and means for maintaining said faces in frictional engagement under pressure.

3. In a machine of the class described, a side gripper for pulling an upper over a last, said gripper being adjustable lengthwise of the last, and a friction clutch normally effective to retain the gripper in any position of said adjustment, said clutch including parts having substantially plane opposed faces frictionally engaged under a pressure permitting adjustment of the gripper to be effected against the friction between said faces.

4. In a machine of the class described, a side gripper for pulling an upper over a last, said gripper being adjustable lengthwise of the last, a friction clutch for retaining the gripper in any position of said adjustment, and power operated means for rendering said clutch effective or ineffective 115 to hold the gripper.

5. In a machine of the class described, a side gripper for pulling an upper over a last, said gripper being adjustably movable different distances lengthwise of the last, means normally effective to retain the gripper in any position of said adjustment, and power operated means for causing said retaining means to release the gripper.

6. In a machine of the class described, a 130

- side gripper for pulling an upper over a last, said gripper being adjustable lengthwise of the last, yielding means for determining a normal position of said gripper 5 while permitting adjustment of the gripper, means for retaining the gripper in adjusted position, and positively operated means for operating said retaining means to release the gripper.
- 10 7. In a machine of the class described, a side gripper for pulling an upper over a last, said gripper being adjustable lengthwise of the last, a clutch for retaining the gripper in adjusted position, and means 15 operative in the final stage of the cycle of operation of the machine to release and then to re-set the clutch.
8. In a machine of the class described, a side gripper for pulling an upper over a last, said gripper being adjustable lengthwise of the last, yielding means for determining a normal position of the gripper, a friction clutch for holding the gripper in 20 adjusted position, said clutch including parts frictionally engaged under pressure 25 permitting adjustment of the gripper to be effected, and power operated means for releasing the clutch to permit the return of the gripper and for then re-setting the 30 clutch.
9. In a machine of the class described, a pair of side grippers for pulling an upper at opposite sides of a last, and gripper positioning means constructed to permit both 35 grippers to be adjusted lengthwise of the last each independently of the other, said positioning means comprising members rotatable for effecting the adjustment of the grippers, connections between said members 40 and the grippers, and means for engaging said members frictionally during such adjustment with pressure sufficient for holding the grippers in adjusted relation.
10. In a machine of the class described, a 45 pair of side grippers for pulling an upper at opposite sides of a last, and means tending to prevent movement of said grippers lengthwise of the last, said means comprising friction clutches and connections be- 50 tween said clutches and the grippers, the clutches being constructed to permit the grippers to be adjusted different respective distances lengthwise of the last while the relatively movable parts of said clutches 55 are in frictional engagement under pressure sufficient to cause the clutches to retain the grippers in adjusted position.
11. In a machine of the class described, a 60 pair of side grippers for pulling an upper at opposite sides of a last, said grippers being adjustable lengthwise of the last each independently of the other, and a friction clutch associated with each gripper for retaining it in adjusted position.
- 65 12. In a machine of the class described, a pair of side grippers for pulling an upper at opposite sides of a last, means for positioning said grippers in a normal relation to each other lengthwise of the last while permitting them to be adjusted lengthwise 70 of the last each independently of the other, means for retaining the grippers in adjusted position, and means for operating said retaining means to release the grippers and permit them to resume their normal relation 75 to each other.
13. In a machine of the class described, a pair of side grippers for pulling an upper at opposite sides of a last, yielding means tending to position said grippers in a normal 80 relation to each other lengthwise of the last while permitting them to be adjusted lengthwise of the last each independently of the other, a friction clutch associated with each gripper for retaining it in adjusted position, 85 and means for operating said clutches to release the grippers and permit them to resume their normal relation.
14. In a machine of the class described, a pair of side grippers for pulling an upper 90 at opposite sides of a last, said grippers being adjustable lengthwise of the last each independently of the other, a friction clutch associated with each gripper and normally effective to retain the gripper in any position of adjustment, said clutches each comprising parts frictionally engaged under pressure permitting adjustment of the corresponding gripper to be effected, and means for operating said clutches to release the 100 grippers at a definite point in the cycle of operations of the machine.
15. A machine of the class described having, in combination, side grippers movable to pull an upper over a last and movable 105 also lengthwise of the last, and operating means for moving the grippers together toward the toe end of the last while in engagement with the upper, said operating means being constructed to permit either 110 gripper to be moved also lengthwise of the last independently of the other gripper.
16. A machine of the class described having, in combination, side grippers movable to pull an upper over a last and movable 115 also lengthwise of the last, and operating means for moving the grippers together toward the toe end of the last while in engagement with the upper, said operating means including parts frictionally retained 120 to permit either gripper to be moved lengthwise of the last independently of the other gripper.
17. A machine of the class described having, in combination, side grippers movable 125 to pull an upper over a last and movable also lengthwise of the last, means for normally positioning said grippers in definite relative locations lengthwise of the last, and operating means for moving the grippers 130

6

together toward the toe end of the last without affecting their relative positions, said positioning and operating means being constructed to permit either gripper to be adjusted relatively to the other lengthwise of the last prior to said combined movement of the grippers.

18. A machine of the class described having, in combination, side grippers movable to pull an upper over a last and movable also lengthwise of the last, yielding means for normally positioning said grippers in definite relative locations lengthwise of the last while permitting adjustment of either gripper relatively to the other lengthwise of the last, means for retaining either gripper in the position to which it is thus adjusted, and means operating through said retaining means to move the grippers together toward the toe end of the last without affecting their relative adjustment.

19. In a machine of the class described, a side gripper movable to pull an upper over a last, said gripper being adjustable lengthwise of the last, means for holding the gripper in adjusted position, and power operated means for rendering said holding means alternately effective and ineffective to hold the gripper.

20. In a machine of the class described, the combination with a gripper adjustable lengthwise of the bottom edge of a last, of a member movable to adjust said gripper, means connecting said member to the gripper, and means for engaging said member frictionally during its adjusting movement with pressure sufficient for retaining the gripper in any position of its adjustment.

21. In a machine of the class described, the combination with a gripper adjustable lengthwise of the bottom edge of a last, of a member movable to adjust said gripper, means connecting said member to the gripper, means for engaging said member frictionally during its adjusting movement with pressure sufficient for retaining the gripper in adjusted position, means tending to return the gripper to a normal position, and means automatically operative at a definite point in the cycle of operations of the machine for relieving the pressure on said adjusting member to permit the return of the gripper.

22. In a machine of the class described, the combination with a gripper mounted for adjustment lengthwise of the bottom edge of a last, of a rack connected to said gripper, a pinion engaging said rack, means for rotating said pinion to adjust the gripper, and a friction clutch comprising members having substantially smooth contacting faces normally in engagement with each other for holding the pinion in adjusted position.

23. In a machine of the class described, the combination with grippers for engaging

an upper at opposite sides of a last, of means for effecting relative adjustment of said grippers lengthwise of the last, said means comprising a rotatable member, and means for engaging said member frictionally during the relative adjustment of the grippers with pressure sufficient for maintaining the adjusted relation of the grippers.

24. In a machine of the class described, the combination with grippers for engaging an upper at opposite sides of a last, of a rotatable member connected to each of said grippers for adjusting it lengthwise of the last, a handle connected to each of said members to permit each member to be rotated independently of the other, and means for engaging each of said members frictionally during the adjustment of the connected gripper, with pressure sufficient for retaining the gripper in adjusted position.

25. In a machine of the class described, the combination with grippers for engaging an upper at opposite sides of a last, of means for moving said grippers together in the same direction lengthwise of the last, said means comprising connections to each of the grippers constructed to permit either gripper to be moved also lengthwise of the last independently of the other gripper.

26. In a machine of the class described, the combination with grippers for engaging an upper at opposite sides of a last, of means for operating said grippers in unison to foredraw the upper, said means comprising connections to each of the grippers constructed to permit either gripper to be moved also lengthwise of the last independently of the other gripper, and means enabling the operator to manipulate said connections for adjusting the upper.

27. In a machine of the class described, the combination with grippers for engaging an upper at opposite sides of a last, of a rotatable shaft, sleeves on said shaft connected to the respective grippers, and means connecting said sleeves to the shaft to cause the grippers to be moved together lengthwise of the last by rotation of the shaft, the connections between the sleeves and the shaft being constructed to permit each sleeve to be turned on the shaft for adjusting its connected gripper.

28. In a machine of the class described, the combination with grippers for engaging an upper at opposite sides of a last, of a rotatable shaft, sleeves on said shaft connected to the respective grippers, and means connecting said sleeves to the shaft to cause the grippers to be moved together lengthwise of the last by rotation of the shaft, said means comprising clutches having parts frictionally engaged under pressure permitting either gripper to be adjusted relatively to the other against the friction of said parts.

29. In a machine of the class described,

the combination with grippers for engaging an upper at opposite sides of a last, of a rotatable shaft, sleeves on said shaft connected to the respective grippers, friction clutches 5 for connecting said sleeves to the shaft to cause the grippers to be moved together lengthwise of the last by rotation of the shaft, said clutches being constructed to permit either sleeve to be turned on the 10 shaft independently of the other for adjusting the connected gripper and then to hold said gripper in adjusted position, and means for operating said clutches at a definite point in the cycle of operations of the 15 machine to release the connection between the sleeves and the shaft.

30. In a machine of the class described, the combination with last and shoe positioning means, of opposite side grippers, 20 manual means for moving said grippers each independently of the other in either direction lengthwise of the last to adjust the upper on the last, spring means for returning the grippers to a normal position, means 25 for retaining each gripper independently in any position of adjustment against the tension of said spring means, and mechanism operative at a definite time in the cycle of the machine to cause said retaining means 30 to release the grippers.

31. In a machine of the class described, the combination with last and shoe positioning means, of a side gripper, manual 35 means for moving said gripper lengthwise of the last to adjust the upper, retaining means continuously effective during such adjustment to prevent retractive movement of the gripper from any position in which the operator leaves it, and means operative 40 subsequently in the normal cycle of the ma-

chine to cause said retaining means to release the gripper.

32. In a machine of the class described, the combination with last and shoe positioning means, of a side gripper movable 45 lengthwise of the last to adjust the upper on the last, and gripper retaining means comprising parts in frictional engagement under pressure sufficient for holding the gripper in adjusted position against the 50 stress of the upper while permitting the adjustment in either direction to be effected by slippage between said parts.

33. In a machine of the class described, the combination with last and shoe positioning means, of opposite side grippers, said 55 grippers being adjustably movable lengthwise of the last each independently of the other, a separate clutch device associated with each gripper to retain it in adjusted position, and a single actuator for controlling both said clutch devices.

34. In a machine of the class described, the combination with last and shoe positioning means, of a side gripper adjustably 65 movable lengthwise of the last, spring means for returning the gripper to a normal position, means comprising a clutch for retaining the gripper in adjusted position, and means operative at a definite time in 70 the cycle of the machine to cause the clutch to release the gripper and then to restore the clutch to holding condition before the machine comes to rest.

In testimony whereof I have signed my 75 name to this specification.

HANNAH ASHTON,
*Executrix of the will of Orrell Ashton,
deceased.*
